The ornamental design for a paver light, as shown and described.

DESCRIPTION

FIG. 1 is a front perspective view of the paver light showing my new design;

FIG. 2 is a side elevation view thereof;

FIG. 3 is a top plan view thereof;

FIG. 4 is a bottom plan view thereof; and,

FIG. 5 is a detail partial cross-sectional side view taken along the line 5-5 of FIG. 3.

The broken lines in FIGS. 1, 2, and 4 illustrate portions of the paver light that do not form part of the claimed design. The broken line in FIG. 5 represents the boundary of the partial cross-sectional view and forms no part of the claimed design.
